UNITED STATES PATENT OFFICE.

OLIVER E. JONES, OF TRINITY VALLEY, BRITISH COLUMBIA, CANADA.

LIFE-RAFT.

1,152,095.

Specification of Letters Patent. Patented Aug. 31, 1915.

Application filed October 14, 1914. Serial No. 866,693.

To all whom it may concern:

Be it known that I, OLIVER E. JONES, subject of the King of England, residing at Trinity Valley, in the Province of British Columbia, Dominion of Canada, have invented certain new and useful Improvements in Life-Rafts; and I do hereby declare the following to be a full, clear, and exact description of the invention, such as will enable others skilled in the art to which it appertains to make and use the same.

This invention relates to a life raft.

An object of the invention is to provide a device of this character which will be practically unsinkable and on which the passenger supporting platform will be mounted in such a way as to be always maintained in a horizontal position irrespective of the position of the supporting pontoons.

20 A further object of the invention is to provide a novel mounting for the supporting platform on the aforementioned pontoons.

With these and other objects in view, such as will appear as the description progresses, 25 my invention comprises the combination and arrangement of parts as herein set forth and falling within the scope of the appended claims.

Referring to the drawing: Figure 1 is a 30 side elevation of my device. Fig. 2 is an end elevation. Fig. 3 is a longitudinal section of one of the pontoons. Fig. 4 is a section on line 4—4 of Fig. 3. Fig. 5 is a section on line 5—5 of Fig. 1. Fig. 6 is a fragmental detail.

Referring to the drawing wherein like parts are indicated by like characters throughout the several views: my device comprises a plurality of parallel pontoons 1 40 held in spaced relation by a plurality of frames 2, the said frames being of rectangular formation. Each of the pontoons consists of an inner tube 3 made of steel or the like and covered with cork 4. This inner tube is inclosed in an outer steel tube 5 of cylindrical formation substantially throughout its length, but turned at the end, as indicated at 6, the ends of the said pontoons being turned inwardly toward each 45 other so that when the device is supported by the lower pontoon the upper pontoon points downwardly toward the water so that when the device is so turned that the upper pontoon rests on the water the end thereof 50 will turn upwardly as will be readily understood. In the outer casing 5 is formed a

plurality of spaced grooves 7 in which are mounted loops 8 on the frame 2 so that there may be no relative movement between the said frames and the pontoons 1.

5 Secured within each of the frames 2 and arranged in a vertical plane is a ring 9 of U-shape in cross section and having a plurality of notches 10 in the inner edges thereof in which are revolvably mounted axles 11 65 on which axles are secured rollers 12, the purpose of which will hereinafter appear.

A second ring 13 of U-shape formation in cross section fits within the legs of the first mentioned rings and the periphery 70 thereof rests on the rollers 12 so that the second mentioned ring, which I will term the inner ring, may have movement with relation to the first mentioned or outer rings and the movement will be greatly facilitated 75 because of the fact that the inner ring bears upon the rollers 12 in the outer rings.

In order that the rollers 12 may be prevented from lateral movement, I have provided washers 14 which are secured to the 80 outer faces of the outer ring 9 between the notches 10 by rivets 15 and which bear against the ends of the axles 11. In this inner ring 13 is formed a plurality of notches 16. Supporting beams 16' are mounted in 85 the notches and extend from the ring in one frame to the ring in the other and so on throughout the length of the device. These beams 16' extend outwardly a considerable distance beyond the endmost frames 2 and 90 a platform 18' is secured to the beams and extends throughout the length of the same on which platform seats may be located.

The object of extending the platform beyond the endmost frames 2 is so that it may 95 be occupied by oarsman to propel the raft.

Secured to each side of the platform between the frames 2 and hanging therefrom to a position adjacent the water are rope ladders 20.

100 In operation when the raft is resting upon two of the pontoons 1 and the platform 18' is supporting weight and is in a horizontal position and because of the roughness of the sea the device is so rolled that the pontoons which rest upon the water are thrown from the water and the device revolved so as to bring two of the other pontoons in the water, the platform 18 maintains its horizontal position because of the fact that the 110 outer ring 9 revolves on the inner ring 13 on which the platform is mounted, thus the rel-

ative motion of the platform and the supporting pontoons may be readily had.

From the foregoing description it may be seen that I have provided a life raft which 5 will be practically nonsinkable and which will be so constructed that the supporting platform will always be maintained in a horizontal position irrespective of the position of the supporting pontoons.

10 I have secured to the pontoons a vertically extending ring in which is mounted a second ring adapted to have motion with relation to said first mentioned ring and on which second ring the beams on which the 15 supporting platform is mounted.

While I have illustrated and described a particular embodiment of my invention, it has merely been for the sake of illustration and I wish it to be understood that I do not 20 want to be limited to that particular embodiment for it is obvious that numerous changes may be made within the scope of the invention as defined by the claims.

What is claimed is:—

25 1. In a device of the class described, a plurality of elongated pontoons, rectangular frames connected to and supporting the same in spaced relation, a ring secured to each of said frames and extending in a vertical plane, rings slidably mounted on the first mentioned rings, a platform secured to the last mentioned rings, and means to facilitate the movement between the first mentioned and last mentioned rings.

30 2. In a device of the class described, a plurality of parallel pontoons, rectangular frames attached to said pontoons in spaced

relation, rings secured to said frames, said rings being of U-shape in cross section and having a plurality of rollers mounted therein in spaced relation, a second ring mounted within each of the first mentioned rings and adapted to rest on the rollers, the said second rings having notches adjacent the lower portion thereof, beams mounted in said notches and extending from the ring in one frame to the ring in the remaining frames, and a platform secured to said beams.

35 3. In a device of the class described, a plurality of parallel pontoons, having curved ends, a plurality of frames secured to said pontoons and extending in a vertical plane, rings of U-shape in cross section secured in said frames, notches in the sides of the said rings, axles revolvably mounted in said 50 notches and having rollers thereon between the sides of the rings, additional rings mounted on the said rollers and within the sides of the first mentioned rings, and beams secured to the last mentioned rings and extending from one to the other.

4. In a device of the class described, a plurality of pontoons, and frames secured to the same and adapted to hold them in spaced relation, said pontoons consisting of inner 55 steel chambers, a cork covering for said chambers, and an outer cylindrical chamber of steel having upturned ends.

In testimony whereof I affix my signature, in the presence of two witnesses.

OLIVER E. JONES.
